UNITED STATES PATENT OFFICE.

FREDERICK W. GRAPPERHAUS, OF CHICAGO, ILLINOIS.

FLUE STRUCTURE.

Application filed April 21, 1919. Serial No. 291,556.

To all whom it may concern:

Be it known that I, FREDERICK W. GRAPPERHAUS, a citizen of the United States, residing at Chicago, in the county of Cook and State of Illinois, have invented certain new and useful Improvements in Flue Structures, of which the following is a specification.

This invention relates to an improved 10 flue structure and it may be embodied in a so-called smoke stack separate from the building walls as is common in power plants, or it may be built into the wall of a building as, for example, in residences or 15 apartment buildings.

Heretofore in building cylindrical smoke stacks of brick it has been customary, upon deciding the exterior and interior dimensions of the stack, to order specially shaped 20 bricks having arcuate faces of the particular curves necessary to fit into the structure to be built so that the inner and outer walls of the stack will be circular in cross-section. It is one of the objects of my invention to 25 provide a flue structure that will permit of the use of standard flat-faced bricks and will permit of the bricks being laid in rectangular formation, while at the same time giving an inner bore of circular cross section 30 which it has been found provides the best draft through the flue.

It is a further object of the invention to produce a flue structure which comprises a sectional lining, each section of which is 35 of square or rectangular exterior and circular interior whereby it permits of the building of square or rectangular brick flues while at the same time providing a circular inner bore which is so desirable.

40 A further object of the invention is to provide, in a sectional structure of the character described, a supporting flange on each section of the lining which is adapted to be built into and virtually form a part of 45 the surrounding brick-work, whereby each lining section is independently supported upon the brickwork and at the same time the flange constitutes a bond in the brick-work to add strength and stability to the 50 latter.

In the accompanying drawings Figure 1 is a sectional view through a flue structure embodying the features of my invention, the lining appearing in elevation. Fig. 2 55 is a horizontal sectional view in which the flue structure forms a part of the wall of

a building, the view being taken in a plane coincident with the upper face of the supporting flange of one of the sections, as indicated by the line 2—2 of Fig. 1. Fig. 60 3 is a perspective view of one of the flue lining sections.

Referring to Fig. 1 which may represent an isolated smoke stack such as is commonly provided for power plants and 65 the like, the brick-work is indicated by the numeral 5 and may be laid in any suitable number of tiers and courses to provide a rectangular opening within. The sections of the flue lining are designated 6 and they 70 may be made of tile or other suitable material. Each section has a rectangular exterior (shown in this instance as square) and it has a central bore or hole 7 extending therethrough which is of circular cross-section. Each section is also provided with a horizontal supporting flange 8 integral therewith which is adapted to be fitted into the surrounding brick-work. The 75 dimensions of the individual sections and the flange 8 thereof are multiples of or directly proportioned to the dimensions of a standard brick, for example, the flange 8 may be approximately equal in thickness and in width to the thickness and width of 80 a single brick. In the preferred form shown in the drawing there is only one flange on each section and it runs continuously around the section, although the number and shape of these flanges may be varied if desired. 90

In Fig. 2 is shown a fragment of a wall 9 of a building in which the smoke stack is built into the wall, the tiers of brick being constructed to form a rectangular space for the flue lining between them. 95

As the brick-work is built up, the lining is put in place, section by section, and the flange 8 takes the place of one row of bricks all around each section. The series of flanges thus form binders at spaced 100 points which add strength and stability to the stack, and each flange independently supports its lining section from the brick-work, so that the lining sections do not rest wholly upon one another. Mortar is of 105 course placed between the abutting ends of the lining sections the same as between the courses of bricks.

The following advantages flow from my invention: The brick-work may be built in 110 rectangular formation, thereby permitting the use of standard bricks instead of spe-

cially shaped arcuate bricks heretofore employed for isolated smoke stacks. At the same time a flue is provided, the interior of which is circular in cross section, thereby giving the best possible draft. The flanges 8 strengthen and stabilize the brick-work and support the lining sections independently so that the whole weight of the column is not carried by the lowermost sections. Expert labor heretofore necessary for building circular flue structures is dispensed with.

I claim as my invention:

1. A flue lining section comprising a body having a centrally located round bore and a rectangular exterior provided with a peripheral flange encircling said body, and lying all in one plane, said flange having a thickness of a single layer of brick or masonry and being centrally located between the ends of the section whereby the section may readily be built into a masonry structure either end up.

2. A flue lining having a plurality of sections, each section comprising a body having a round bore and an angular exterior and flat end faces, the total length of said body being equal to the thickness of an odd number of layers of brick, and a single centrally located integral peripheral flange encircling and projecting from said body and lying all in one plane, the thickness of said projection being equal to the thickness of a brick and width of said projection being equal to the width of a brick whereby said sections may be conveniently built into a brick structure either end up, being supported in place partly by the engagement of said flange with the brick structure and partly by abutment of the lower end of each section upon the flat face of the section below.

In testimony whereof, I have hereunto set my hand.

FREDERICK W. GRAPPERHAUS.
